LLOYD BLACKMORE, OF DETROIT, MICHIGAN, ASSIGNOR TO FRIGIDAIRE CORPORATION,
OF DAYTON, OHIO, A CORPORATION OF DELAWARE

REFRIGERATING APPARATUS

Original application filed June 15, 1922, Serial No. 568,534. Divided and this application filed January 24, 1928. Serial No. 249,170.

The present invention relates to control apparatus and is a division of my copending application Serial No. 568,534, filed June 15, 1922 (F-170).

5 One of the objects of the present invention is to improve control apparatus so that a relatively wide range of adjustment can be obtained and to provide for a relatively high degree of change in the adjustment 10 quickly.

Another object is to provide a control apparatus having an adjustable device for the normal control thereof and a modifying device for the apparatus which when actuated 15 will not disturb the setting of the adjustable device.

The invention contemplates a control apparatus having an operating member and an adjustable resistance mechanism therefor 20 which normally regulates the operation of the operating member, in combination with a yieldable resistance device for modifying the operation of the operating member, which can be moved at will into and out of effective 25 operative relation with the operating member. This device is arranged so that it will not disturb the normal setting of the adjustable resistance mechanism.

Further objects and advantages of the 30 present invention will be apparent from the following description, reference being had to the accompanying drawings, wherein a preferred form of the present invention is clearly shown.

35 The present invention is herein shown for illustrating purposes only, in connection with a refrigerating system wherein it is desirable to provide normally a certain temperature and wherein it is desirable at times to obtain temporarily a different temperature.

In the drawings:

Fig. 1 is a front elevation of a refrigerator, 40 with parts broken away, and

Fig. 2 is a detail view, on an enlarged scale.

The adjusting device will take different forms to accommodate the different types of control mechanism but in any event the lever 50 or handle for operating the adjusting mechanism will be located in a position convenient to the operator. The device is preferably provided with a plate or dial located on the refrigerator having suitable legends thereon 55 indicating to what position to move the hand or lever for fast or slow freezing, as is clearly indicated on Fig. 2 of the drawings.

For simplicity of illustration and convenience in description, the refrigerating mechanism is shown more or less diagrammatically and only such parts of the same are shown as are necessary to an understanding of the construction and operation of my invention and its application to said mechanism. The 60 device is shown as being associated with an automatically operated domestic refrigerator of the compression type in which a fluid thermostat is employed, but it is understood that the same principle may be employed 65 on any type of refrigerators employing this on other forms of thermostats or other equivalent control devices.

70 On the drawings, the reference character 10 designates a refrigerator cabinet having the refrigerating or cooling chamber 11; the food or cooling compartments 12 and 13; and the lower compartment 14 for enclosing the motor 15 and the automatic controlling mechanism 16, all of which are of the usual 75 or well-known construction.

Since the specific construction of the controlling mechanism constitutes no part of my invention it is not thought necessary to describe all the details of said mechanism. The 80 controlling mechanism shown is that employed in a well-known make of refrigerators now on the market and is the same as that disclosed in application Serial No. 146,715 of Bechtold and Mellowes, filed February 5, 85

1917, now Patent No. 1,478,421, dated December 25, 1923, in which a pressure actuated mechanism, controlled by a weight 17 is employed for controlling the water valve and in which a fluid thermostat located within the refrigerator is employed to operate the electric switch for controlling the compressing motor, said means including a yieldable resistance device arranged to be movable at will 10 into and out of effective operative relation with said member. As shown, a diaphragm 18 is adapted to be expanded by fluid pressure to operate the lever arm 20 on which is secured the weight 21. The forward end of the arm 20 has attached thereto the weight 22 to which is connected the link 23 which operates an electric switch located in the switch box 24.

When the fluid in the thermostat expands 20 it elevates the lever 20 and permits the weight 22 to carry the switch operating link 23 downwardly to close the switch and when the fluid in the thermostat cools it contracts and permits the weight 21 to descend thus causing 25 the link 23 to be elevated to open the switch.

The temperatures at which the electric switch is opened and closed depends upon the adjustment of the control mechanism. In practice, the device is properly adjusted at 30 the factory and when once adjusted the adjustment is not to be disturbed except by, or under the supervision of, an expert. It is often desirable, however, to temporarily adjust the control so that the refrigerator may 35 be temporarily maintained at a considerably lower temperature, as when the user wishes to hasten the freezing process. In order to accomplish this temporary adjustment without the assistance of an expert, suitable mechanism arranged within convenient reach of 40 the operator is provided whereby the control mechanism may be adjusted with facility, at the will of the operator.

In the embodiment disclosed, this mechanism 45 comprises a resilient member such as the spring 25, the lower end of which is adapted to be connected to the outer end of the lever arm 20 by any suitable means, as the link 26, which extends through an enlarged opening 50 26a in said lever arm. The link is provided at its lower end with nuts whereby the effective operation of said spring may be properly adjusted. The upper end of said spring is adapted to be connected to the outer end of 55 an arm 27 on the shaft 28. The shaft 28 is journaled in the front wall 29 of the refrigerator and has the operating handle 30 attached to the front end thereof.

Any suitable means may be provided for 60 retaining the handle in adjusted position. As shown, a plate or quadrant 31 having suitable legends thereon is secured to the front face of the wall 29 and may have the shaft 28 journaled therein. The plate or quadrant 31 is 65 provided with means for holding the handle

30 in any one of a plurality of positions. As shown, the plate or quadrant is provided at the sides thereof with the stops 32 and 33 for limiting the downward movement of the handle when it is in either extreme position. The lever and arm are so arranged that when the arm is on the stop 33 the tension of the spring will hold the handle against said stop. While the handle is shown as being held in only two positions it is understood that it 75 may be otherwise.

During the normal operation of the refrigerator the handle 30 is in the position shown in Fig. 1 in which the spring is not in tension and the rod 26 is free to slide through the opening 26a as the lever 20 moves up and down during its normal operation.

When it is desired that the temperature of the refrigerator shall be lowered in order to hasten the freezing process, or, for any other reason it is desirable to lower the temperature of the refrigerator, the handle 30 is moved to the right in contact with the stop 33, as shown in Fig. 2, which will place the spring 25 under tension and will thus assist in supporting the weight 20. This will permit the fluid thermostat to lift the weight 21 at lower temperatures to open and close the switch for the compressing motor and will thus result in materially lowering the temperature of the interior of the refrigerator. The temperatures at which the freezing chamber will now be maintained will depend on the adjustment of the tension of the spring 25 but in any event, water, desserts, etc. placed within the refrigerating chamber may be frozen in a much shorter period of time than is possible in the normal operation of the refrigerator.

As previously stated herein, the present invention is shown as applied to a refrigerating system merely for the purpose of illustrating a use thereof and it is to be understood that such control apparatus is equally applicable to other types of systems.

While the form of embodiment of the invention as herein disclosed constitutes a preferred form, it is to be understood that other forms might be adopted, all coming within the scope of the claims which follow.

What is claimed is as follows:

1. A control apparatus including a movable operating member, means for operating said member, means for modifying the operation of said member including a spring, a dial, means for moving the spring into and out of effective operative relation with said operating member throughout its entire range of movement, said last mentioned means including means cooperating with the dial for indicating the position of the spring.

2. A control apparatus including a movable operating member, means for operating said member, resistance means for modifying the operation of said member, a dial, means

for varying the effect of said resistance means, said last means also being operable for moving the resistance means into and out of effective operative relation with said operating member throughout the entire range of movement of the operating member, said last means including means cooperating with the dial for indicating the position of the resistance means.

10 In testimony whereof I hereto affix my signature.

LLOYD BLACKMORE.
